UNITED STATES PATENT OFFICE.

THOMAS SHIPLEY, OF YORK, PENNSYLVANIA.

CONDENSER FOR ICE-MAKING AND REFRIGERATING MACHINES.

1,079,609.

Specification of Letters Patent.

Patented Nov. 25, 1913.

Application filed October 30, 1912. Serial No. 728,577.

To all whom it may concern:

Be it known that I, THOMAS SHIPLEY, of York, in the county of York and State of Pennsylvania, have invented a new and useful Improvement in Condensers for Ice-Making and Refrigerating Machines, of which the following is a specification.

My invention relates to condensers, and more particularly ammonia condensers, for use in refrigerating and ice making plants, and it consists in certain improvements designed to enhance the efficiency of the condenser, and to obtain effective condensing action with much less cooling surface than is employed in existing types of condensers of this class.

The improvements will first be described in connection with the accompanying drawings, forming part of this specification, and will then be more particularly pointed out in the claims.

In the drawings—Figure 1 is a longitudinal vertical section of so much of a “coil” condenser as needed to illustrate my invention as applied to this form of condenser. Fig. 2 is a similar view of a modification. Fig. 3 is a vertical axial section of a “shell” condenser embodying my invention.

Referring now to Fig. 1, the body of the condensing coil, like that of the usual standard condenser, is formed of a pipe which extends continuously without a break in horizontal stretches or lengths $A' - A^{10}$, the return bends a of this pipe being suitably connected to the straight stretches or lengths (in this instance ten in number) of the pipe. The cooling water used enters the overhead distributing trough x and through suitable perforations in the bottom of the same is showered down upon the coil below as customary in this style of condenser.

The bottom stretch A' is connected directly with the top stretch A^{10} by a stand pipe or riser C which forms part of the coil. The coil is thus composed in effect of an endless pipe through which the contents of the coil can travel in a closed cycle.

The ammonia gas from the compressor is led to the condenser through the pipe b , and enters the condensing coil at the bottom. Before entering the coil at this point I prefer to subject it to a preliminary cooling, and to this end the pipe b opens into a preliminary section composed of a pipe coil B of two lengths or stretches connected at one end by a return bend b' , the upper length

of B being connected with a short length of pipe c (here shown in the form of a nozzle) which enters the stand pipe C at or near the bottom of the same and extends up therein so that its discharge end will be some little distance above the point where the stand pipe joins the bottom length A' of the coil, the nozzle being of sufficiently less diameter than the pipe to leave between the two an annular space somewhat similar to the annular space around the lifting steam nozzle of an injector. Through this annular space the ammonia liquid can pass from the bottom length of the condenser coil into the stand pipe, in which pipe the liquid, when the condenser is at rest, will stand at the same level with the liquid in the body of the condenser. The ammonia gas entering the stand pipe C through the injector nozzle c is forced into the body of liquid contained in said pipe.

The valve controlled outlet for the condensed and cooled liquid is indicated at D as located on the second length A^3 above the bottom length A' of the coil. It may be located at any desired point on the coil, but in order to take off the liquid where it is coldest, I prefer to place said outlet as near the bottom as consistent with maintaining a sufficient height of liquid column in the stand pipe.

The coil B , to which I lay no claim, serves, as in other condensers heretofore in use, to take out the sensible heat of the ammonia gas before it enters the condensing coil where the principal work of condensation is done. It is not a necessity, however, and may be dispensed with, in which event the pipe b from the compressor would be connected directly to the inlet nozzle c . I prefer to use it as an adjunct of the coil, inasmuch as it takes the sensible heat from the gas, thereby doing work which would otherwise have to be done in the condenser proper.

E is a “purge” valve such as customarily used on ammonia condensers.

Assuming the condensing coil to be supplied with liquid ammonia at the outset, to say the level of the outlet D , the operation is as follows: The ammonia gas from the compressor, after passing through the pre-cooler B , enters the stand pipe C through the nozzle c from which it is injected into the column of ammonia liquid in the stand pipe, the result of thus bringing the gas into contact with the liquid being the condensation

of the gas, the heat of which is taken up by the liquid, the work of condensation being effected as soon as actual and complete contact takes place. The continuing action of the entering jet upon the superincumbent column of ammonia liquid in the stand pipe is to force the liquid before it and to lift the same up in the stand pipe until it passes over into the top stretch A¹⁰ of the condenser 5 coil whence in liquid form it passes down by gravity in due course to join the body of liquid contained in the lower part of the condenser. The work of condensation is practically complete before the top stretch 10 of the condenser coil is reached, and that coil is used to cool an already condensed gas, instead of being used, as heretofore, first to condense the gas and afterward to cool the resultant product, thus enabling me to reduce 15 very materially the area of cooling surface required. The circulation in the condenser is in practically a closed cycle, in the direction of the arrows, such portion of thereof as is the accumulation due to the 20 condensation of the gas being taken off, as it gathers, through the outlet D. The liquid coming over from the stand pipe is effectively cooled during its downward passage through the coil, and when it reaches the bottom 25 stretch A', whence is drawn the supply for the stand pipe, it is several degrees cooler than the critical temperature due to the pressure within the coil—that critical temperature (the temperature at which the gas 30 liquefies) varying directly, as is well known, with said pressure. The low temperature of this body of its own liquid into which the entering ammonia gas is injected assists materially in the work of condensation. 35

40 The gas injecting nozzle may be located at some other point on the condenser than the stand pipe C. For example, in Fig. 2 the nozzle c is represented as located in the end of the bottom stretch A' opposite to that 45 from which the stand pipe C leads, passing, for this purpose through a special return bend a' connecting this end of the bottom stretch with the stretch A² next above. The ammonia liquid passes down from above 50 through this bend into the bottom stretch A', there being an annular passage for this purpose between the nozzle and the interior of the condenser pipe. Like letters of reference in Figs. 1 and 2 indicate corresponding 55 parts. The operation of the condenser is the same as that of the condenser in Fig. 1, save that the work of condensation in this case is done mainly, if not entirely, in the bottom stretch A' before the stand pipe C is reached. 60

65 It will be noted that under this arrangement the ammonia gas is discharged into the liquid contained in the bottom of the condenser, where the work of condensation chiefly takes place, and the resultant is conveyed from that point directly to the top of the con-

denser, through which it passes down again to the bottom of the condenser to meet the entering gas, the circulation being in practically a closed cycle, with provision for taking off the liquid as it accumulates beyond the volume required for successful operation of the condenser, the liquid in the bottom of the condenser into which the entering gas is forced being constantly renewed by a supply drawn from the coolest portion of the liquid contents of the condenser. This I believe to be new with me beyond its special structural embodiment here described and illustrated. 70

The same mode of operation and effect 80 may be had in a "shell" condenser, as will be understood by reference to Fig. 3. In this figure, the body of the condenser, as usual in condensers of this type, is composed of a vertical shell F, closed at each end by 85 a tube head f of suitable known construction, filled with tubes g which extend the length of the shell, suitable water connections being provided as shown to maintain a circulation of cooling water through the 90 tubes g, these tubes serving to cool the contents of the tank. The water circulation is indicated by the arrows. From the lower part of the shell, where the ammonia liquid is coolest, is taken out a riser or stand pipe 95 C', which enters the top of the shell above the level of the liquid therein, as shown. Into the lower part of this pipe, through a suitable fitting, enters the nozzle c', through which the ammonia gas from pipe b is 100 forced into the body of ammonia liquid with which the stand pipe at that point is filled. The action of this nozzle c' is precisely that of the nozzle c in the condenser coil of Fig. 1. Communicating with the bottom and top 105 of the condenser is another vertical pipe h, on which are located the liquid ammonia outlet D', corresponding to the outlet D of Fig. 1, and also, if preferred, the purge valve E. The outlet could be connected 110 directly to the shell, but for convenience sake it is located on the pipe h. The level of the ammonia liquid in the condenser, and the stand pipe C', when the condenser is inactive, is indicated at l. The mode of operation of this apparatus is substantially the same as that of the apparatus shown in Fig. 1. The ammonia gas is injected into the superincumbent column of its own liquid contained in the stand pipe, and the resultant passes up through the stand pipe into the top of the shell, where it meets the cold water tubes g, and passes down to join the body of the liquid ammonia below, the liquid as it cools descending to the level 1 where it passes back into the pipe C' again, and the surplus liquid of condensation passing off through the outlet D'. 115

I do not herein claim broadly the combination of a condenser, comprising a con-

denser body and a return pipe connecting the ends of the same through which the contents of the condenser may circulate in a closed cycle, with a gas nozzle through 5 which the gas to be condensed is injected under pressure directly into the body of liquid contained in the condenser whereby circulation of the contents of the condenser is set up in a direction to constantly renew 10 the body of liquid, at the injecting point with a supply drawn from that end of the condenser which contains the cooled liquid, and means for taking off the liquid of condensation as it accumulates, inasmuch as 15 the same is the subject of my application filed February 28, 1913, Serial No. 751,252.

Having described my invention and the best way known to me of carrying the same into practical effect, I state in conclusion 20 that I do not restrict myself to the structural details hereinbefore set forth in illustration of my invention, since, manifestly, the same can be varied considerably without departure from the spirit of the invention: But

What I claim herein as new and desire to secure by Letters Patent is:

1. In a condenser, and in combination, a 30 pipe communicating with, and adapted to receive a constant supply of the liquid contained in, the lower portion of the condenser; a gas inlet or nozzle from which the gas to be condensed is injected under pressure into the body of liquid contained 35 in said pipe and means for maintaining the

level of the liquid above said inlet; and a riser leading from said pipe to, and opening into, the top of the condenser, through which riser the product resulting from the injection of the gas into the body of liquid 40 contained in the pipe is conducted directly into the top of the condenser to pass down over the cooling surfaces therein to the body of liquid below, substantially as and for the purposes hereinbefore set forth. 45

2. In a condenser, and in combination, a pipe communicating with, and adapted to receive a constant supply of the condensed liquid contained in, the lower portion of the condenser; a gas inlet or nozzle from 50 which the gas to be condensed is injected under pressure into the body of liquid contained in said pipe; a riser leading from said pipe to, and opening into, the top of the condenser, through which riser the 55 product resulting from the injection of the gas into the body of liquid contained in the pipe is conducted directly into the top of the condenser to pass down over the cooling surface therein to the body of liquid below; and an outlet for the liquid located at a higher level than the gas inlet, substantially as and for the purposes hereinbefore set forth. 60

In testimony whereof I affix my signature 65 in presence of two witnesses.

THOMAS SHIPLEY.
